UNITED STATES PATENT OFFICE.

WILLIAM H. MALLORY, OF BRIDGEPORT, CONNECTICUT, ASSIGNOR OF ONE-HALF TO THOMAS F. ROWLAND, OF BROOKLYN, NEW YORK.

ROCKET-TORPEDO.

SPECIFICATION forming part of Letters Patent No. 249,192, dated November 8, 1881.
Application filed May 2, 1881. (No model.)

To all whom it may concern:

Be it known that I, WILLIAM H. MALLORY, of the city of Bridgeport, State of Connecticut, have invented a new and useful Improvement 5 in Rocket-Torpedoes, of which the following is a full, true, and exact description, reference being had to the accompanying drawings.

My invention consists in a torpedo which is arranged to be propelled by the gas produced 10 by the burning of some gas-producing substance, and in the peculiar construction and arrangement of the powder-burning devices, and in a novel method of compensating for the loss of weight of the torpedo due to the destruction of the powder or other gas-producing 15 material, and that which I consider novel in my apparatus is claimed in the claims hereto annexed.

In my drawings similar letters refer to similar parts.

Figure 1 represents a view, partly in section and partly in elevation, of the forward half of my torpedo; and Fig. 2, a similar view of the stern end of my torpedo. Fig. 3 represents a 25 view, in section, of two of my cartridge-holding devices; and Fig. 4, a view of one of them in perspective. Fig. 5 is a section through Fig. 3 on the line *x x*.

A represents generally my torpedo, which 30 does not materially vary in external configuration from the torpedoes ordinarily employed, being cylindrical and more or less pointed at both ends. The stern end is provided with wings or fins *W*, for the purpose of turning the 35 torpedo upon its axis as it advances through the water.

The forward chamber, *V*, of my torpedo may be charged with any suitable explosive, to be fired in any well-known way, and the novelty 40 of my construction will be found in the powder-chamber and stern end of my torpedo.

I arrange the powder which is to propel my torpedo in a number of small cartridges arranged to be simultaneously burned, instead of 45 using one cartridge of considerable extent. By this device, and by burning these cartridges simultaneously through a considerable length of my torpedo, I am enabled to equalize the effect upon the torpedo of the loss of weight, and 50 to make the burning of the powder uniform

throughout the entire extent. It is very apparent that if a single cartridge of considerable length and weight be burned the center of gravity of the entire torpedo must be varied as the combustion of said powder advances, 55 while by dividing the powder into short sections, and also by inclining those sections with reference to the axis of the torpedo, I avoid, as far as possible, the longitudinal shifting of the center of gravity of the torpedo-boat. Further, by the arrangement of a number of independent cartridges or charges simultaneously burning I am enabled to burn at all times during the burning of the charge the same quantity of powder by exposing the same area of 60 surface for combustion.

I prefer to arrange my charges in a number of independent cartridge-holders, which are in their general configuration hollow cones. These may be made of any suitable material; but I find 70 compressed papier-mâché to be very suitable. These cartridge-holders and the contained charges are shown in detail in Figs. 3, 4, and 5, as before referred to. The cartridge-holder itself consists of a thick hollow cone, *L*, pierced 75 longitudinally. These cones are likewise pierced with a series of circular cavities, whose axes are parallel to their outside surfaces. These cavities are marked *G*, and may be readily seen in Fig. 3. I then prepare suitable 80 cartridges of compressed gunpowder, which are arranged to burn uniformly and for a long enough time to enable the torpedo to complete its determined course. I do not limit myself to compressed gunpowder, as other slow-burning 85 gas-producing bodies might be used. These compressed cartridges are then forced into the cavities *G*, previously described. The cartridge-shells *K* are adapted exactly to fill the cavities *G*. A suitable number of these cartridge-holders having been prepared, I prefer 90 to place them in my torpedo as follows: I first slip the requisite number of cartridge-holders over a central stem or mandrel, and force them loosely together. I then fill the angles formed 95 at the base of the cones with fire-clay *P*, and then slip the combined cartridge-holders and fire-clay within the metallic shell of the torpedo. The rearmost cartridge-holder is adapted to bear against a circular support, *F*, as shown, 100

and the foremost cartridge-holder is confined by the screw-cap N. By screwing down this screw-cap N, or by drawing the cartridge-holders together on the mandrel, the conical cartridge-holders are firmly forced together, and it will be found that they form a practically continuous whole, by reason of their locking against each other, and the fire-clay is forced outward and against a surrounding metallic shell, so that the completed structure is solid, and firmly located within the metallic shell. This metallic shell has preferably a spiral channel cut upon its surface. Surrounding the central section of the torpedo, and extending over so much of the torpedo as is acted on by the powder, is an elastic tube, which may be made of india-rubber or other suitable material. This elastic tube or casing is arranged to be filled with a sufficient quantity of air to exactly float the weight of powder which is to be consumed. In other words, the weight of water displaced by reason of the presence of air within the casing should be as nearly as possible equal to the weight of the powder to be consumed. Suitable apparatus is provided for filling this expansible casing with air, and I provide the spiral channel, before referred to, in order that the air-pressure may be simultaneously applied throughout the entire extent of this casing, although it is not absolutely necessary in all cases. The air-chamber within the expansible casing D connects with the air-chamber E in the stern of the torpedo by means of time-orifices R. The chamber E communicates with the combustion-tube by free orifices T. When the torpedo is charged and ready for use these orifices T are arranged to be closed by a plug, S, which also closes the open end of the combustion-chamber and protects the charge. By this arrangement of a collapsing air-casing I am enabled to exactly compensate for the loss of weight in the torpedo due to the burning of the powder, and to simultaneously and equally compensate for this loss of weight throughout the entire length of the torpedo within which the charge is being consumed.

It is plain that the expanding diaphragm D might be arranged in several ways so as to produce the same result and in the same way. For instance, it might be located within the exterior metallic casing of the torpedo, or two chambers might be provided, one at either end of the cartridge-chamber, and by freely connecting the same and allowing the contained air to escape the same result might be accomplished.

It will be found that an apparatus constructed like the one before described will, owing to the natural laws governing the flow of gases under varying pressures, operate to reduce the displacement of the expansible diaphragm uniformly during the same periods of time until the air has been entirely driven out, and I make use of this law to uniformly and equally compensate for the burning of the powder, so that it will be found that my tor-

pedo as a whole will have the same specific gravity at all times during the combustion of the powder and the escape of the air.

The operation of my torpedo will now be readily understood. The metallic shell having been properly charged with cartridges, as previously explained, I proceed to inflate the diaphragm D, which may be done by any suitable valve, the plug S having been previously driven into the end of the combustion-chamber, as shown. This plug is to be provided with a suitable exploder, the one I prefer being an apparatus to fire a charge of loose powder through and to the end of the central opening, around which the cartridges are placed, thereby simultaneously firing all the cartridges. This exploder may be ignited by electricity or in any other suitable way. The torpedo having been placed in position in the water, and properly directed to strike the desired object, the exploder is fired and the explosion immediately drives out the plug S. Then the powder, burning regularly, by its reaction forces the torpedo forward at a high velocity. At the same time the air within the diaphragm, being released, flows out through the time-orifices R and the free openings T, and escapes with the products of combustion, and thereby, as before explained, the specific gravity of the torpedo remains unaltered, and it pursues the same direction in which it was originally aimed. The fins W, by rotating the torpedo on its axis, cause it to pursue a straight line in its forward motion.

What I claim as my invention, and desire to secure by Letters Patent, is—

1. A rocket-torpedo provided with a number of independent radially-arranged propelling-charges, and means, substantially as described, whereby said charges may be simultaneously fired.

2. A rocket-torpedo provided with a number of independent charges located at different points in the length of the vessel, and means, substantially as described, whereby said charges may be simultaneously fired, to burn at the same time, without affecting the center of gravity of the vessel, as set forth.

3. A rocket-torpedo in which separate powder-receptacles are arranged in diverging lines from the axis of the torpedo outward, with their mouths toward the center, substantially as and for the purpose set forth.

4. A rocket-torpedo provided with a compensating collapsing diaphragm or chamber having a time-discharge orifice, substantially as described.

5. A rocket-torpedo provided with a compensating collapsing diaphragm or chamber, which chamber is provided with a time-orifice whose area allows the collapsing of the chamber simultaneously and coincidently with the burning of the powder, substantially as described.

6. The combination, in a rocket-torpedo, of a series of independent cartridges adapted to be simultaneously fired, and the collapsing dia-

phragm having a time-discharge orifice, substantially as described.

7. A rocket-torpedo provided with a number of annular or conical cartridge-holders adapted to be charged and subsequently placed in position in the torpedo, substantially as described.

8. In a rocket-torpedo, the combination of a collapsing compensating-diaphragm the chamber of which is provided with a time-orifice, and a plug confining the air within the diaphragm-chamber and adapted to be driven

from the torpedo, thereby releasing the air by the explosion of the powder, substantially as described.

9. A rocket-torpedo in which the propelling-charge is arranged within a series of separate independent pockets radially arranged, and all communicating with a central chamber open toward the rear, substantially as set forth.
